UNITED STATES PATENT OFFICE.

JOHN ANDREW LARSON, OF GLENDALE, NEW YORK.

OIL-BURNER.

1,378,689.

Specification of Letters Patent. Patented May 17, 1921.

Application filed June 2, 1920. Serial No. 385,992.

To all whom it may concern:

Be it known that I, JOHN A. LARSON, a citizen of the United States, and resident of Glendale, in the city of New York, borough 5 of Queens, county of Queens, and State of New York, have invented a new and Improved Oil-Burner, of which the following is a full, clear, and exact description.

My invention relates to a burner, and 10 more particularly an oil burner, and aims to provide a device of this nature which may be used with extreme economy and improved results for commercial and house heating purposes.

15 In connection with certain types of oil burners it is well appreciated that difficulty has been experienced in adequately vaporizing the fuel, due to the constantly declining quality of the same.

20 Also difficulty has been experienced in obtaining an instant response of the apparatus when it was desired to immediately extinguish the flame.

Having these defects in mind, I have now 25 constructed a burner, by means of which primarily, a more desirable flame will be produced in that the volatile fluid will be more readily and thoroughly vaporized by virtue of the fact that the air is introduced 30 in such a manner as to insure that the same will act as a most efficient vehicle for the oil or other volatile fluid used, further insuring an intimate co-mingling and minute subdividing of the particles forming the fuel 35 mixture.

Reference is had to the attached sheet of drawings as illustrating one practical embodiment of my invention, and in which drawings,

40 Figure 1 is a side view, partly in section, of a complete burner unit.

Fig. 2 is a plan view of the burner, and

Fig. 3 is a sectional view taken along the lines 3-3 of Fig. 1.

45 In these views, the reference numeral 5 indicates the reservoir adapted to contain a volatile fluid which is connected to a feed tank 6 by any suitable means, such as a flexible piece of tubing 7, the feed tank being in turn connected by a similar tubing 8 to the burner.

Contrary to the conventional construction, the feed tank 6 is slidably mounted so 55 that the same is movable in a vertical plane, this being accomplished for a purpose hereinafter more fully set forth, by any suit-

able means such as a slide 9 formed with a rack 10 into which the teeth of a gear 11 project, this gear being conveniently mounted upon a shaft 12 capable of rotating, 60 which shaft may have a ratchet 13 associated with it, which ratchet co-operates with a pawl 14, the tank 6 being secured to the slide 9.

The tank has conveniently positioned 65 within it, any suitable valve of a float control type 15, which insures the maintenance of a constant level of volatile fluid 16 within the tank 6.

The burner conveniently includes a casing 70 17 providing a burner bowl 18 in its upper face through which extends tubes 19 their outer ends projecting into the atmosphere, their inner ends communicating with the interior of the casing 17. Connected with the casing by means of a tube 20, is an air compressor 21, which introduces air under pressure into the casing 17, this air consequently escaping through the tubes 19. The tube 8 connects with a pipe 22 having one of 75 its ends extending beyond the casing 17, its opposite end projecting through the upper face of the casing, and being conveniently centrally disposed within the burner bowl 18.

It will now be understood by virtue of the well known law of physics that "fluid seeks its own level" that by moving the tank 6 upwardly by means of the mechanism provided therefor, that a certain portion of the 90 volatile fluid 16 will flow through the tubing 8, pipe 22 and so into the burner bowl 18, this fuel being replenished by virtue of the float valve 15. Upon compressed air being applied by means of the blower 21, 95 in lieu of the natural draft now commonly used, a certain amount of the fluid 16 within the burner bowl will be picked up by the air and will be capable upon ignition of producing a most desirable type of flame. 100

Obviously it will be appreciated that the more the tank 6 is elevated by the mechanism provided for this purpose, the greater will be the flow of fluid through the tubing 8 into the burner bowl 18, and the higher 105 the fluid will rise within this portion, thus moving nearer to the upper edges of the tubes 19 and constantly being more readily picked up by the air escaping therefrom. Upon the tank 6 being lowered however, the 110 fluid will feed less rapidly into the burner bowl, and will also occupy a lower plane,

thus moving farther from a point adjacent to the upper face of the tubing 19 and consequently not being subjected to as constant a sucking action as before.

- 5 When it is desired to completely and instantly extinguish the flame within the burner bowl, this may be done by continuing to lower the tank 6, whereupon the upper level of the fluid within the tank will 10 be lower than that of the fluid within the bowl, thus causing the fluid within the bowl to flow rearwardly through the pipe 22 and tubing 8 and return to the tank 6.

It will be appreciated that danger might 15 exist in this operation of the flame being carried into the tank 6, and with a view of eliminating this danger, the upper end of the pipe 22 is conveniently inclosed by means of a screening or other suitable element 20 23, and it will readily be understood that by means of this screening that any danger of a flame passing into the pipe 22 is precluded.

From the foregoing it will be understood 25 that I have constructed a burner in which the flame may be regulated with that degree of nicety insuring the production of the temperature desired, and by means of which a more intense and desirable flame will be 30 produced.

Obviously numerous modifications of structure might be resorted to without in

the least departing from the scope of my claims.

What I claim as new is:

1. A burner, including a bowl, tubes extending through said burner bowl and terminating at a point above the same, a feed pipe having one of its ends projecting through said burner bowl at a centrally located point within the same, and a screening enveloping the end of the feed pipe, said screening extending within the burner bowl.

2. A burner, including a reservoir, a feed tank and a casing connected one to the other, said feed tank being movable in a vertical plane, and having means adapted to maintain fluid within the same at a constant level, said casing presenting a burner bowl 50 in its upper face, tubes extending through the base of said burner bowl, and communicating with the interior of the casing, and the outer atmosphere, a source of compressed air communicating with the interior 55 of said casing, and a feed pipe having its inner end extending through the face of said bowl and terminating at a central point within the same, said feed pipe being in communication with the tank, and means 60 associated with said feed pipe and within the burner bowl for preventing the passage of flame into the pipe.

JOHN ANDREW LARSON.
